UNITED STATES PATENT OFFICE.

JOHN WESTGATE, OF BRIMSTAGE, AND CHARLES E. H. HAWKEN, OF WALLASEY,
ENGLAND.

RAILWAY-CAR AND LIKE VEHICLE.

1,384,500.

Specification of Letters Patent. Patented July 12, 1921.

Application filed January 18, 1919. Serial No. 271,881.

To all whom it may concern:

Be it known that we, JOHN WESTGATE, subject of the King of Great Britain, residing at Brimstage, Cheshire, England, and 5 CHARLES EDMUND HENSLEY HAWKEN, subject of the King of Great Britain, residing at Wallasey, Cheshire, England, have invented certain new and useful Improvements in or in Connection with Railway- 10 Cars and like Vehicles, of which the following is a specification.

This invention has reference to railway cars and the like vehicles of the kind that are convertible at will, from flat bottom cars 15 to self discharging hopper cars and vice versa, so as to render them suitable for carrying granular or other material in bulk (such as for example coal, salt or grain), or for carrying other freight such as packages 20 or bales of merchandise. The advantages of such vehicles are that they will carry one class of merchandise in one direction and another class in the other direction, thus effecting a very great saving in the number 25 of vehicles employed which is very important desideratum.

Prior to this invention, it has been proposed to provide this kind of vehicle with floor doors so hinged that they could be 30 turned upward to take up a perpendicular position but leave an open space through which the bulk material could leak out, if the side doors were accidentally or mischievously left open.

35 The present invention has been more especially designed to avoid this difficulty while providing a vehicle in which the entire interior space is made available for the transport of bulk material.

40 This invention will be understood from the following description, reference being had to the accompanying drawings in which:—

Figure 1 shows a longitudinal elevation 45 of the vehicle partly in section.

Fig. 2 shows a transverse section of the vehicle.

Fig. 3 in plan one construction of convertible vehicle or car made according to 50 this invention.

Fig. 4 is a detail view showing the arrangement of the overlapping edges for the floor doors.

Fig. 5 shows in longitudinal section, and

Fig. 6 in cross section a construction of 55 convertible covered car.

Fig. 7 shows in front elevation the apparatus for loading the car with bulk material at the starting station.

Fig. 8 is a sectional plan view of a 60 convertible car showing the arrangement when only one hopper is provided.

Referring first to Figs. 1, 2 and 3, the car comprises a body having discharging or loading doors 1 at the sides 2 and formed 65 with a hoppered bottom 3 whose outlets 4 are controlled by sliding valves 5 so as to discharge the load downward. In the example shown there are three independent hoppers 3 each having four sides converging 70 toward the central outlet 4 and the underframe is constructed with transom bars 6 and a longitudinal central bar 7 in addition to the usual side sills 8 and end sills 9. The four downwardly extending sides of each 75 hopper which converge toward the center outlet 4 are suspended from the members of the underframe and are additionally supported and strengthened by means of the members 11, and fillets or sill members 12 80 triangular in cross section are inserted between the top of the hoppers and the car sides which form an upward extension or prolongation of the former. The car is converted from a hopper bottom car into a 85 flat bottom one by means of a supplemental floor composed of pairs of floor doors 13 extending the full length of the vehicle body and hinged inside the body at opposite sides by the strap hinges 14 whose hinge pins are 90 shown at 15. These floor doors are so made and arranged that when raised to make the vehicle available for bulk material, they lie substantially perpendicular against the vehicle sides and extend to the top of the side 95 openings in the vehicle body so as to completely close the said openings and prevent leakage of bulk material therethrough. These floor doors however can be closed down flat to form a flat bottomed car to 100 carry merchandise which does not require to be discharged through the hopper bottom, in which position they rest on the underframe with their meeting edges 16 on the longitudinal bar 7 so as to form a close 105 cover for the hoppers. When these doors are lifted into an upstanding position to lie against the sides, then the entire interior

space of the car is available for the transportation of grain or other material in bulk, fastening devices such as 17 being provided to hold them in that position. These floor doors when raised effectively close the side openings in the car body even should the side doors be mischievously opened into the position shown at 1^x while the fillets or sill members 12 close any open space below the doors through which the bulk material could leak out. If the sides are higher (or the body narrower) than that shown then the meeting edges of these doors 13 are made with rabbets 18 in such manner as to overlap and lie coincident with one another when in the closed position as shown in Fig. 4. This insures that the doors when raised shall reach to the top of the sides.

The opening at the bottom of each hopper is normally closed by a sliding plate or valve 5 which is adapted to be opened in a transverse direction by a hand wheel 19 secured to spindle 20 having a pinion 21 which gears into a toothed rack 22 on the door, this mechanism being external to the vehicle. The spindle is journaled in bearings 23 cast on the plates 24 which are secured to the discharge opening 4 of the hopper in such manner that a space or way is left between, for the valve to slide in when the hand-wheel 19 is operated. By this means delivery of material through each discharge opening can be regulated. The valve 5 is held locked in the position into which it has been set, by a pin 26 passed through a hole in the bracket 23 and wheel 19. The floor doors can be raised or lowered by hand in which case a pair of floor doors are preferably provided in connection with each hopper, or they can be raised or lowered by winding gear as will be described presently in which case there is one pair of doors only, extending the full length of the car.

When the invention is applied to a covered goods car the sides of which extend to a greater height as shown in Figs. 5 and 6, each floor door 27 which is made of sheet metal, extends in opposite directions from their hinges across the entire width of the body inside when closed to form a close cover for the hoppers 3 and lie over one another. These floor doors 27 when in the raised position effectively close the side openings in the car body should the side doors (not shown) be mischievously opened. To the horizontal edge 28 of one door opposite to the hinge 29 and at both ends, are firmly secured chains 30 which are guided upward by the sheaves 31 (secured to the body) and then downward to the guide sheaves 32 and drums 33 on the longitudinal shaft 34 which is journaled in the brackets 25. This shaft is operated by handwheel 35 and worm 36 which gears with the worm wheel 37 on the said shaft. The other door 27 is operated in

a similar way, one door being raised or lowered first by the handwheel 35 at one side of the car, and then the other door by the hand-wheel 35 at the other side of the car. The covered car is loaded with packages of merchandise through side doors as usual, but when converted into a hopper car it is loaded with bulk material through openings in the roof which openings can be closed by sliding doors 38. It will thus be seen that when the floor doors lie flat, they cover the hoppers 3 below and form a floor upon which the merchandise or packages rest, and leave the doors at the sides quite free for loading or discharging freight but when the floor doors are raised on their hinges into the upright position, the hoppers 3 form the bottom of the car which can then be filled with material in bulk, such material being unloaded by opening the valves 5 so as to discharge downward. A convenient method of loading the car with bulk material without hand manipulation is shown in Fig. 7, in which the loading is effected from storage bins 40 by swiveling chutes 39 and a convenient method of discharging the car is to place the wagon over an endless belt conveyer which is erected between the rails of the track, this conveyer being adapted to deliver the bulk material to an elevator or weigher for delivery as required. In this way a car can be used for many varieties of merchandise that have to be conveyed by rail from place to place.

When only one hopper is provided at mid-length of the vehicle, then the floor doors 13 extend over the open space above the said hopper so as to cover the same as shown in Fig. 8 when the vehicle is to be used for carrying packages or bales of merchandise. When however the doors 13 are raised on their hinges, they take up a substantially upright position between the fixed bars 42 which are located on the inside of the car at each side of the door opening, thus preventing the bulk material escaping through the side openings should the ordinary discharge doors 1 be left open.

By this invention a car can be used on the outward journey for one description of freight (for instance grain in bulk) and on the return journey for another kind of merchandise thus utilizing rolling stock to the fullest possible extent, and avoiding having to waste power in hauling of empty cars.

We declare that what we claim is:—

1. In a railway freight-car or like vehicle of the type convertible from a flat into a hopper-bottom vehicle, the combination with the vehicle sides, the side-sills, and hopper bottom, of triangular fillets inserted between the top of the hoppers and the vehicle sides, and a supplemental floor for said vehicle comprising a number of floor doors, each of which is pivotally connected to a fil-

let, whereby to close any space between the lower edge of the floor doors when raised and the top of the hoppers.

2. In a railway freight-car or like vehicle of the type convertible from a flat into a hopper-bottom vehicle, the combination with the vehicle sides, the side-sills and hopper bottom, of strengthening angle-pieces between the top of the hoppers and the side sills, triangular fillets between the top of the hoppers and the vehicle sides, and a supplementary floor for said vehicle comprising a number of floor doors hinged to the fillets.
3. In a railway freight-car or like vehicle of the type convertible from a flat to a hopper-bottom vehicle, the combination with the vehicle sides, side-sills and hopper bottom, of hinged floor doors extending across the vehicle in opposite directions from

the hinges and lying one on top of the other when in the closed position, and means for raising and lowering said doors comprising a longitudinal shaft journaled at each side of the vehicle, winding drums at the ends of each shaft, chains passing over guide sheaves at the upper part of the vehicle and secured at one end to the edges of the respective floor doors and at the other end to the drums, and hand-wheels and worm-gearing for operating said longitudinal shafts.

In witness whereof we have hereunto signed our names this 21st day of December, 1918, in the presence of two subscribing witnesses.

JOHN WESTGATE.
